UNITED STATES PATENT OFFICE.

ERNEST E. MINARD, OF DETROIT, MICHIGAN.

FEED COLLET.

Application filed April 13, 1925. Serial No. 22,749.

This invention relates to feed collets used in automatic and hand-operative screw-machine, bar-forming machine, and the like for feeding stock so that end or intermediate portions of the stock may be operated upon for the production of screws and other articles of manufacture. A feed collet is adapted to intermittently advance the stock and a well known type of collet includes resilient fingers formed from a tubular piece of material and adapted to have the finger ends frictionally grip a piece of stock and advance it axially of the tubular piece of material.

My invention has special reference to that class of collets wherein the finger ends are provided with detachable and interchangeable pads or gripping jaws, and in this class of collets some trouble has been experienced by the pads or jaws becoming displaced when a piece of stock encounters the same.

The primary object of my invention is to provide a set of pads or jaws for a collet with positive and reliable means, as herein-after set forth, for preventing endwise displacement of the pads or jaws when encountering a piece of stock.

Another object of this invention is to provide collet jaws with means for preventing circumferential shifting of the jaws in a collet, said means having an engagement with the collet fingers that does not interfere with the resiliency of the fingers nor weaken the same to the extent of decreasing the efficiency of the collet.

The above are a few of the objects attained by my improvement and others may appear as the nature of the invention is better understood by reference to the drawings, wherein

Figure 1 is a side elevation of the collet, partly broken away and partly in longitudinal section;

Fig. 2 is a cross sectional view taken on the line II-II of Fig. 1;

Fig. 3 is a cross sectional view of the collet showing the manner of forming opposed openings in fingers of the collet;

Fig. 4 is a side elevation of a set of pads or jaws for the collet; and

Fig. 5 is an end view of the same.

In the drawings, the reference numeral 1 denotes a collet adapted to be placed in a machine and reciprocated therein to intermittently feed a piece of stock 2. The collet 1 is formed from a cylindrical body or

tube longitudinally slotted, as at 3, to provide opposed resilient fingers 14.

Adjacent the outer end of the collet are opposed arcuated slots 4 disposed transversely of the fingers and extending through the fingers with the outer ends of the slots of less area than the inner ends, this being brought about by using a rotary cutter or other instrumentality 5 to form the slots. 60 The rotary cutter may be placed in the end of the collect and moved first into engagement with one finger 14 and then the other finger, as brought out in Fig. 3, thus producing the slots with parallel side walls and 65 curved end walls, the curved end walls being designated 6 and curving inwardly from the inner walls of the fingers 14 to the outer walls thereof.

Mounted in the outer end of the collet is 70 a set of opposed pads or jaws 7, each substantially semi-cylindrical to form a passage 8 for the piece of stock 2 which is adapted to be frictionally engaged by the pads or jaws to be advanced when the collet is shifted in a feeding direction, the pads or jaws sliding on the piece of stock to obtain a fresh purchase or grip thereon when the collet recedes for such purpose.

The inner ends of the pads 7 are beveled 75 inwardly from the outer cylindrical wall of the pad to the inner wall thereof, as at 9 so that these beveled walls may cooperate in providing a sloping easy entrance into the passage 8 for an end of the stock 2, thus 80 preventing the pads from receiving an end blow that would tend to force the pads from the outer end of the collet.

On the outer cylindrical walls of the pads 85 7 are substantially crescent shaped lugs or abutments 10 adapted to extend into the slots 4 and substantially fill said slots, said lugs having side walls or shoulders 11 and curved end walls 12, the side walls or shoulders 11 preventing longitudinal movement 100 of the pads in the collet and the end walls 12 preventing circumferentially shifting of the pads. The lugs 10 have an arcuated length approximately half the semi-circumference of each collet finger, such being in 105 contradistinction to any shoulder or abutment that is semi-circular or semi-cylindrical, for it is obvious that the slots 4 could not be made completely semi-circular. In cutting the slots 4 through the fingers 14 110 there is a maximum depth for the lugs 10 effective for preventing longitudinal shift-

ing of the pads, and while there is a maximum inter-engagement between the pads and the fingers, yet the outer walls of the fingers are not interrupted and cannot 5 interfere with any reciprocation of the collet.

In practice the lugs 10 will snugly fit in the slots 4 but, if for any unforeseen reason the lugs should become loose in the slots 4 10 one pad will simply approach the other and not become fully disengaged from its finger, because of the proximity of the longitudinal edges of the pads. Should one of the pads fall on to the other the lug 10 of the fallen 15 pad still extends into the slot 4 of its finger and a piece of stock encountering the beveled ends 9 of the pads will simply raise the fallen pad and establish the proper relation between the pad and its finger for an operation 20 action of the collet as a feeding device.

The abrupt deep side walls or shoulders 11 of the lugs 12 are essential to prevent any endwise slippage of the pads and it is by virtue of these side walls or shoulders that 25 it is practically impossible for a piece of stock to force the pads endwise from the outer end of the collet. It is obvious that the pads are interchangeable for stock of various diameters or cross sectional shapes 30 and that the mounting of the pads within the outer end of the collet does not interfere with the resiliency of the fingers 4 in functioning as stock feeding means.

There are various ways of producing the 35 lugs 10 on the pads 7 and in practice I prefer to machine the outer walls of the pads for accurate formation of the lugs, so that there will be a positive interlocking of the pads and collet fingers. In view of this 40 practice, a method is involved which consists in internally cutting collet fingers to provide opposed open slots, and then machining the outer walls of pads to form lugs adapted to snugly fit in the slots of the 45 collet fingers, one pad being first placed in position and then the other, so that the pads are positively retained within the collet against accidental displacement by a piece of stock contacting therewith.

It is thought that the utility of my invention will be apparent without further description, and while in the drawing there is illustrated a preferred embodiment of my invention, it is to be understood that the structural elements are susceptible to such 55 variations and modifications as fall within the scope of the appended claims.

What I claim is:—

1. A feed collet having opposed resilient fingers formed with slots, and pads between said fingers and backed up against outward radial movement by the finger walls, said pads being formed with transverse abrupt shoulder portions for engagement with side walls of said finger slots. 60

2. A feed collet slotted to provide opposed resilient fingers, each finger having a slot adjacent the outer end thereof, opposed pads in said collet providing a stock passage having a beveled entrance, said pads having walls flush with the slit walls of the fingers, and means on said pads extending into and filling the finger slots to prevent longitudinal and circumferential shifting of said pads relative to said fingers. 70

3. A feed collet as called for in claim 2, wherein said pads are non-yieldable in an outward radial direction and said means has a configuration which may permit said pads to move towards each other without disengagement from said fingers to the extent of permitting longitudinal shifting of the pads relative to said fingers. 75

4. A feed collet as called for in claim 2, wherein said means is in the form of lugs having abrupt deep side walls engaging similar walls of said finger slots. 80

5. A feed collet comprising resilient fingers, pads set against the inner walls of said fingers and free to move inwardly towards each other, and abrupt shouldered lugs preventing longitudinal displacement of said pads relative to said fingers. 90

6. A feed collet as called for in claim 6 wherein said lugs are radially disposed relative to the axis of said collet. 95

In testimony whereof I affix my signature.
ERNEST E. MINARD.
